THOMAS W. RYAN, OF CONCORD JUNCTION, MASSACHUSETTS.

BALL-COCK.

1,163,370.

Specification of Letters Patent.

Patented Dec. 7, 1915.

Application filed March 9, 1914. Serial No. 823,280.

To all whom it may concern:

Be it known that I, THOMAS W. RYAN, a citizen of the United States, residing at Concord Junction, county of Middlesex, 5 State of Massachusetts, have invented an Improvement in Ball-Cocks, of which the following description, in connection with the accompanying drawing, is a specification, like characters on the drawing representing like parts.

This invention relates to improvements in ball cocks and comprises broadly the production of a ball cock which will work effectively and quietly whether used upon 15 high or low pressure fluid supply systems.

It is well known that the pressure varies in different water systems and in fact in the different portions of the same system, as, for example, in the different levels of high 20 buildings so that certain portions are under high pressure and others under low pressure. It has been found that ball cocks adapted for use upon the higher pressures are ill adapted for use on low pressures, and that if a 25 high pressure ball cock for a flush tank is used upon very low pressure systems the delivery will be so slow as to require an undesirably long period to fill the tank. It is further found that unless a large ball is 30 used in such cases the valve will chatter or sing when closing. On the other hand, if a ball cock adapted for low pressure is used upon a high pressure system the rapid flow of water will cause an undesirable noise.

35 So far as I am aware no ball cock has hitherto been devised which has been adapted to deliver fluid to a tank from either high or low pressure systems with substantially equal efficiency and noiselessly in each 40 case.

One of the objects of the present invention is to produce a ball cock which may be readily adjusted for high or for low pressure systems without the necessity of using 45 balls of different sizes.

Another object of the invention is to provide means for silencing the delivery of the fluid through a ball cock which is used upon a high pressure system and which means 50 will not unduly retard the flow of the fluid pressure when applied to a low pressure system.

Another object of the invention is to provide a simple and effective means whereby 55 the ball will be supported above the bottom

of the tank when the fluid in the tank is drawn off, so that the ball will be kept clear and free from contact with any sediment which may be present in the bottom of the tank. 60

Another object of the invention is to provide a simplified ball cock in which the valve casing and pivotal support for the ball lever may be conveniently cast in a single piece and which may be assembled 65 and dismantled conveniently.

Another object of the invention is to provide a ball cock casing with a series of integral members which may be bored at a single operation to provide accurately alined 70 bearings for the valve piston, whereby the sticking or jamming of the valve will be obviated.

Other objects of the invention and the nature thereof will more fully appear from the 75 accompanying description and drawings and will be particularly pointed out in the annexed claims.

In the drawings, Figure 1 is a vertical longitudinal sectional view of a ball cock 80 embodying the preferred form of my invention, the piston being shown in elevation; Fig. 2 is a similar view of a modified and simplified form of ball cock embodying certain features of the invention; Fig. 3 is an 85 elevation of the end of the valve casing showing the adjustable bearing for the ball lever which operates the valve; Fig. 4 is a like view of a modified form; Fig. 5 is a vertical sectional view on the line 5—5, Fig. 2; 90 Fig. 6 is a sectional view of the piston taken on the line 6—6, Fig. 1.

The preferred form of the invention illustrated in Fig. 1 of the drawing comprises a casing 1 having screw threads 2 at its inlet 95 end adapted to be engaged by a coupling 3 to secure it to an inlet pipe 4. The barrel of said casing is preferably cylindrical in form and has a spherical enlargement 5 toward its opposite end which terminates in a 100 pair of extensions 6, forming bearings for the pivots 7, 8, of a ball lever 9 which may be connected to a ball (not shown) by a rod 11 in the usual manner and which is adapted to operate a suitable piston valve 10. The casing 1 is preferably provided with a T-shaped 105 integral stand 12 adapted to be secured on the edge of the tank 13 by screws 14 or other suitable fasteners and with a discharge pipe 15 preferably depending from the spherical en- 110

largement 5 having an internally screw threaded end to receive a pipe (not shown) leading to near the bottom of the tank. The spherical portion 5 of the casing desirably 5 may be provided with a web or partition 16 adapted to form a bearing for the piston 10, and also to deflect the flow of the fluid to the discharge orifice, the eductive action of the stream serving to prevent leakage 10 through the outer bearing. The casing thus described may be cast in a single piece, suitable cores being provided to give the interior thereof substantially the desired shape. It may then be bored directly from one end 15 to the other providing a series of bearings 20, 21 for the piston accurately alined with the cylindrical portion in which the valve reciprocates.

The opposite or inlet end of the valve case 20 is preferably provided with a ground conical bearing 25 adapted to coöperate with a complementary tapered bearing 26 on the end of the inlet pipe to clamp the conical end of a valve seat firmly in place. The valve seat 25 may desirably be provided with a cylindrical portion 27 fitting snugly within the cylindrical bore of the casing; the inner end of the valve seat may be provided with a groove 28 adapted to engage a relatively 30 soft valve member 30 desirably of leather or rubber secured to the end of the piston 10 in any suitable manner as by means of a screw 31.

In order to silence the flow of water 35 through the ball cock when the same is used upon high pressure systems and yet to provide for an effective discharge when it is used upon a low pressure system, the portion of the piston within the cylindrical casing 40 is desirably provided with a pair of series of baffle plates or deflecting wings 32, 33, which are preferably made integral with the piston and disposed alternately on opposite sides thereof, the adjacent ends overlapping to provide sinuous channels for the 45 passage of the fluid through the cylindrical portion of the casing so that the fluid passing through the casing will take the course indicated by the arrows in Fig. 1. It will be noted that these baffle plates, which are 50 located alternately on opposite sides of the piston, preferably above and below, overlap only a relatively small distance and that the chambers between the baffle plates of each 55 series are relatively wide and long so that the water is permitted to flow quite freely along the sinuous course indicated by the arrows in Fig. 1 when it is under a relatively low pressure. When however the 60 water is under a high pressure so that it is being forced rapidly through the delivery chamber it is divided into two streams one on each side of the piston. The force exerted against the baffle plates tends to divert 65 these streams into spirals traveling in oppo-

site directions around the stem of the piston with a considerable centrifugal force. These spiral streams meet alternately on one side and the other of the piston, thus opposing each other and forming eddies which retard the otherwise rapid flow of the water from the discharge orifice and render the discharge end of the tank substantially noiseless. It is found that the amount of such interference or retardation of fluid increases substantially in proportion to the increase of pressure or heat of the water so that for high pressures the amount of retardation due to the interfering spiral streams is much greater than the retardation 70 effected under low pressure when the water flows more nearly in the undulating path indicated by the arrows in Fig. 1. It has therefore been found in practice that this arrangement sufficiently retards the velocity 75 or flow of the fluid in high pressure systems to cause a substantially noiseless discharge without so impeding the progress of the fluid when used upon low pressure systems as to unduly delay the refilling of the 80 tank.

The portion of the piston within the spherical part of the casing is preferably of full diameter and fits tightly in the bearings 20 and 21, thereby preventing leakage 85 through the end of the casing. The end of the piston is desirably provided with a flat integral extension 40 having a hook shaped portion 41 providing a slot 42 adapted to receive a shaft or stud 43 carried by 90 arms 44 of the bell lever 9. The hook shaped portion is preferably provided with a strengthening rib 45. The end of the piston may desirably be provided with extensions having shoulders 46 adapted to engage 95 the arms 44 of the ball lever to limit the downward movement of the ball in the tank, and to retain it above the bottom thereof free from contact with the sediment which may be deposited in the tank.

It will be noted that when the pivot 7 of the ball lever is in its lowest position when being used on a low pressure system the piston 10 will have a longer traverse before the shoulders 46 engage the arms 44 of the ball lever than when the ball lever is pivoted in the high position when used upon the high pressure system. It will therefore be obvious that the greater withdrawal of the piston 10 when operating upon the low pressure system will permit the water to flow more freely than when the traverse of the piston is more limited. This is an important feature in a ball cock which is adapted to be placed upon either a high pressure 105 or a low pressure system. The shaft 43 may be provided with anti-friction rings 47.

The extensions 6, of the casing 1 may be provided with depending ears having oppositely drilled bearings 50 and 51, adapted 110

to receive the pivots 7 of said ball lever 9 which desirably may be screw-threaded into the arms 44 of the lever 9. The bearings 50 desirably are located at a distance 5 below the axis of the piston just sufficient to cause the axis of the shaft or stud 43 to cross the longitudinal axis of the piston whereby the ball lever will act upon the piston in a substantially straight line coincident with the axis of the piston, thereby 10 eliminating as nearly as possible all frictional resistance of the piston in its bearings and permitting the application of the maximum power to open and close the valve 15 which is desirable when the same is used upon a high pressure system.

The bearings 51 are preferably arranged substantially in the plane of the axis of the piston so that when the ball lever is mounted 20 in these bearings the shaft or stud 43 will lie in the upper portion of the slot 42 in the piston extension and will act upon the piston eccentrically of its axis. This provides a cam-like action which will increase 25 the frictional resistance of the piston sufficiently to prevent the chattering or singing of the valve upon closing when it is used in low pressure systems. By reason of this arrangement the improved ball cock may 30 be used on either high or low pressure systems without the necessity of using balls of different sizes.

If desired the bearings 50, 51 may be connected by a slot 52 as illustrated in Fig. 4, 35 thus making it unnecessary to dismantle the lever to effect the adjustment of the pivots, it being sufficient to partially unscrew the pivotal screws until the smaller portions thereof may be moved in the slot 52.

The construction illustrated in Fig. 2 40 differs from that illustrated in Fig. 1 in that the valve seat 27 is relatively long, extending into the spherical portion of the casing, and in that the deflecting and silencing ribs 45 of the piston have been omitted. It further differs in that no means are provided for adjusting the pivotal supports for the ball lever 9. This modified form of ball cock is more cheaply manufactured and may be 50 used in many instances especially where it is not important that the noise of the running water should be subdued.

It is to be understood that while I have 55 illustrated this invention in the preferred form it may be embodied in other constructions without departing from the spirit thereof.

Having thus described my invention what I claim as new and desire to secure by Letters Patent is:

1. A ball cock comprising a relatively long casing having a cylindrical chamber provided with inlet and outlet orifices, a valve seat at the inlet end of said casing, a piston 65 journaled in the other end of said casing and

having a cylindrical stem terminating in a valve adapted to engage said valve seat, a series of baffle plates alternately arranged at intervals within said cylinder on opposite sides of the piston and overlapping at their 70 adjacent ends whereby the water is caused to flow through said chamber in a divided stream, the paths of which follow combined sinuous paths and intersecting spiral courses whereby the fluid by interference and eddy- 75 ing causes greater retardation of the flow upon high pressure than upon low pressure.

2. A ball cock comprising a relatively long casing having a cylindrical chamber with outlet and inlet orifices, a valve seat, a series 80 of baffle plates on said piston arranged alternately upon opposite sides thereof and overlapping each other at their adjacent ends whereby the fluid by interference and eddy- 85 ing causes greater retardation of the flow upon high pressure than upon low pressure.

3. A ball cock comprising a relatively long casing having an inlet orifice at one end and a lateral outlet orifice adjacent its other end, 90 said casing being bored longitudinally from said inlet orifice through the opposite end to form a piston bearing and a chamber of equal diameter, a valve seat in the inlet end of said chamber, a piston having a bearing 95 of equal diameter to said bore, journaled in the opposite end of said casing and having a reduced stem terminating in a valve adapted to engage said valve seat, a series of segmental cylindrical baffle plates on said piston 100 arranged alternately upon opposite sides thereof, fitting closely said chamber and overlapping at their adjacent ends whereby the fluid by interference and eddy- 105 ing causes greater retardation of the flow upon high pressure than upon low pressure.

4. A ball cock comprising a valve casing having an inlet orifice and a lateral outlet orifice, parallel integral extensions beyond said outlet provided with a plurality of cylindrical journal bearings connected by slots 110 narrower than the diameter of said bearings, a valve seat within said casing, a co-operating piston valve having an offset slotted extension, a ball lever having a member slidably seated in the slot in the piston extension and adapted to engage the walls of the slot in the piston either in the axial plane of the piston or eccentrically thereof, and removable screw threaded fulcrum members 115 having portions of different diameter adapted normally to be seated in said journal bearings but when partially unscrewed to slide freely in the slots in said casing extension whereby the engagement of the ball 120 lever with the piston may be axially thereof or eccentric to said axis.

5. A ball cock comprising a valve casing having an inlet orifice and an outlet orifice, parallel extensions beyond said outlet orifice- 125

vided with journal bearings, a valve seat within said casing, a coöperating piston valve having a slotted extension and shoulders adjacent to said slot, a ball lever pivotally mounted in said casing extensions and having a member engaging the slot in said piston extensions and shoulders upon said ball lever arranged to engage the shoulders on said piston when the ball reaches a prede-

termined depression whereby said ball will be retained above the bottom of the tank.

In testimony whereof, I have signed my name to this specification, in the presence of two subscribing witnesses.

THOMAS W. RYAN.
